LOW WATER ALARM

Hans A. Bohuslav, Los Angeles, Calif., assignor
to Engineering Controls, Inc., Los Angeles,
Calif., a corporation of California

Application December 6, 1948, Serial No. 63,680

13 Claims. (Cl. 123—41.15)

1

This invention relates to control systems and devices.

A main object of the present invention is to provide new and useful improvements in control devices for indicating low water and excess pressure conditions.

A main object of the present invention is to provide a control device for a chamber containing water and steam that is simple and inexpensive and which will indicate not only when there is a low water condition within the chamber but will also indicate increases in pressure within the chamber.

Another main object of the present invention is to provide a control device for a chamber containing water and steam which control device provides an unobstructed passage from the liquid in the chamber to the air outside the chamber and in which a thermal responsive control means is positioned directly in the path of flow of fluid through the passageway.

Another main object of the present invention is to provide a control device which provides an air tight subchamber extending outwardly from the chamber below the water level therein and which control device is actuatable when the water within the chamber falls below the subchamber.

Another object of the present invention is to provide a system including a control device associated with a vapor phase unit which vapor phase unit is used to cool the cooling water of a prime mover, and in which system the control device is adapted to turn off the prime mover when there is a low water condition in the chamber.

Another object is to provide a system as above set out wherein the control device will turn off the prime mover when there is an excess steam within the vapor phase unit or when there is an excess pressure within the vapor phase unit.

With the foregoing and other objects in view, which will be made manifest in the following detailed description and specifically pointed out in the appended claims, reference is had to the accompanying drawings for an illustrative embodiment of the invention, wherein:

Fig. 1 discloses a sectional elevation view of a vapor phase unit with the control device associated with the condenser of the vapor phase unit;

Fig. 2 discloses a vapor phase unit with the control device directly associated with the body of liquid within the vapor phase unit; and

Fig. 3 discloses a vapor phase unit in which the control device is directly associated with the

2

liquid in the chamber of the vapor phase unit.

Referring to the accompanying drawings wherein similar reference characters designate similar parts throughout, various embodiments of the present invention are disclosed and are shown as associated with a vapor phase unit although it is to be understood that while the present invention has been adapted for the vapor phase unit as will be described that the invention is not intended to be limited to a vapor phase unit as the invention will lend itself to other systems such as boilers and the like.

One form of the vapor phase unit is shown in Fig. 1 and this vapor phase unit is usually used with some sort of prime mover, for instance, such as a diesel engine, a gasoline internal combustion engine or a natural gas engine or a turbine or various other devices in which cooling liquid must be supplied to a prime mover. In the vapor phase system, the cooling liquid is conveyed from the prime mover to the vapor phase system at approximately boiling temperature and in the vapor phase system the liquid may be immediately expelled or drawn out from the vapor phase unit and used over again while the vapor passes to a condenser where it is condensed and the liquid condensed from the vapor is returned to the liquid body within the vapor phase unit. It can be seen then that the vapor pressure within such a system is slightly above atmospheric as contrasted to a steam boiler system wherein the pressure may be 50 pounds per square inch, 100 pounds per square inch or up.

The vapor phase unit disclosed in Fig. 1 comprises a chamber 10 adapted to contain a volume of liquid 11 which liquid is conveyed to the chamber 10 by a conduit 12 from a prime mover not shown and the liquid 11 is conveyed away from chamber 10 by conduit 13. The pipe 12 in some vapor phase systems conveys the cooling liquid into the chamber 10 tangentially of the chamber so that the liquid whirls about within chamber 10 and forms a liquid surface 14, as shown in Fig. 1.

There is generally some sort of shielding means 15 in the bottom of the chamber 10 to provide a quiescent zone and there may be an extension 17 on the conduit 13 extending upwardly within chamber 10 so that any impurities, mud or the like will be collected around the portion 17 and will not be returned to the prime mover.

There is a plurality of shields 20 and 21 provided within chamber 10 to serve as a separator for the liquid vapor mixture that rises upwardly

through shield 20 and around shield 21. There is a drain pipe 22 leading from shield 20 down into chamber 10 below the liquid level therein so as to be sealed by the liquid. The steam condensing within shield 20 will therefore flow down drain 22 into chamber 10.

A condenser generally entitled 24 is usually mounted above the liquid vapor chamber 10 and may be mounted on the top of chamber 10 and has a header 25 communicating with chamber 10 as shown in Fig. 1 and there is a second header 26 which has a liquid return pipe or conduit 28 leading therefrom which conduit leads down below the liquid level in the chamber 10 a point somewhere near the low water mark of the chamber. There are a plurality of conduits 30 leading from header 25 to header 26 and these conduits may have fins 31 provided thereon and there is some sort of means such as a fan 33 for drawing air by or over the conduits 30.

The vapor rising up in header 25 will be condensed and it flows through conduits 30 and the liquid condensed from the vapor will flow down through header 26, conduit 28 and back to chamber 10.

In the control set up as shown in Fig. 1 the control device is connected to the header 26 preferably at the upper part thereof and comprise a conduit 36 which leads outwardly from header 26 and which conduit has a thermal responsive means 37 mounted thereon with the lower portion of the thermal responsive means depending down within conduit 36.

The thermal responsive means 37 may be of any of the usual types such as a bi-metallic strip, or a low melting point mass of metal which is heated when contacted by steam to release a contact and either to make or break a circuit. Instead of the thermal responsive means 37 there may be an audible means such as a whistle inserted in the place of thermal responsive means 37.

It is preferable that the thermal responsive means 37 be connected to the prime mover so as to cut off or turn off the prime mover whenever the thermal responsive means is actuated. Vapor phase units are widely used with prime movers in localities where constant attention to the prime movers is not possible nor desirable and, therefore, these prime movers operate without attention and therefore the present invention provides some means for automatically cutting off the prime mover if the water level within chamber 10 should fall below a predetermined low level and the control device will also operate whenever an excess load is applied to the prime mover or whenever the fan belt breaks on the prime mover or when any other event occurs which causes excess heating of the fluid 11.

The operation of the device disclosed in Fig. 1 is as follows. In such a system as described there is generally a constant volume of liquid in the cooling circuit and should this constant volume be decreased by leaks or other causes so that the water level 14, shown in Fig. 1, drops below the lower end of conduit 28, then the steam or vapor within chamber 10 will exit through conduit 28 out through conduit 36 and thereby heat thermal responsive means 37 which in turn will cut off the prime mover. The thermal responsive means 37 will not be actuated by the vapor rising up into header 25 because this vapor is cooled and condensed by passing through conduits 30 and so that there is only liquid within header 26 or

possibly some air which can escape through conduit 36.

If, on the other hand, there is overheating of the cooling liquid above the capacity of the condenser 30 and so that an excess pressure is created within chamber 10 then the steam or vapor will not all be condensed within conduits 30 and will then pass into header 26 and out through conduit 36 contacting thermal responsive means 37 and actuating thermal responsive means to cut off the prime mover.

It will be seen then that the control device in Fig. 1 is adapted to be actuated by low liquid level conditions and also by excess pressure or excess steam conditions.

In Fig. 2, the chamber 40 is a chamber such as chamber 10 and there is a conduit 41 communicating with the liquid space within chamber 40 and this conduit 41 extends outwardly from the chamber 40 and then upwardly above the water level 43 in chamber 40 and exits at 45. Conduit 41 may have fins 46 on the vertical part thereof as shown in Fig. 2.

There is a thermal responsive means 48 provided in the upper end of conduit 41 which thermal responsive means extends downwardly so as to be directly in the path of flow of any fluid which passes through conduit 41.

In both the set ups shown in Figs. 1 and 2 there is an unobstructed passage from the liquid space in the chamber to the air outside the chamber so that there is permanent communication between the liquid space and the air.

The device in Fig. 2 operates as follows. Whenever the water level therein falls to a point such as 49 the vapor or steam within chamber 40 may then pass out of chamber 40 and through the conduit 41 and out through 45 and in doing so will flow over and around the thermal responsive means 48 to heat up the thermal responsive means which will be actuated to cut off the prime mover.

The device as shown in Fig. 2 will not be actuated under ordinary conditions since the water in conduit 41 will only rise to a point substantially even with the liquid level 43 within chamber 40 and the rest of conduit 41 will not have air therein which forms an insulating medium between the thermal responsive means 48 and the water or liquid within the lower part of conduit 41.

The device shown in Fig. 2 will also function as an excess pressure device since whenever the pressure within chamber 40 increases to an extent such that water or liquid is forced out through conduit 41 up through the vertical part of conduit 41 and out through the portion 45 then this liquid will be in contact with the thermal responsive means 48 and will actuate the thermal responsive means 48 to turn off or cut off the prime mover.

By positioning the thermal responsive means 48 directly in the path of flow of any fluid which passes through conduit 41 a quicker and more reliable response by the thermal responsive means 48 are insured.

It will be appreciated that by the present invention all floats or valve members or moving parts or the like have been eliminated and a reliable and simple control device has been provided to guard against low water conditions and excess pressure conditions.

In the device in Fig. 3 there is control chamber 51 of similar construction to control chamber

10 wherein there is a conduit 53 providing a sub-chamber extending out in a horizontal direction from chamber 51 and in this case the outer end of conduit 53 is sealed by a plug 54 or other suitable means so that an air tight subchamber is provided for chamber 51.

It is important that the conduit 53 be horizontal for if it were tilted upwardly there would be a good likelihood that air would be trapped within the conduit 53 which would insulate the thermal responsive means 55 and therefore resulting in very unreliable operation of the system.

However, since the conduit 53 is in a horizontal position the liquid within chamber 51 will flow into and completely fill the conduit 53. Cooling fins 57 are provided on conduit 53 and, therefore, there will be a temperature differential between the liquid at the outer end of the conduit 53 and the liquid within chamber 51 and this temperature differential is sufficient so that the temperature responsive means 55 will not be actuated when the liquid level is normal. However, when the liquid level falls down below conduit 53 the liquid within conduit 53 will flow into chamber 51 and the vapor within chamber 51 will then flow into conduit 53 contacting thermal responsive means 55 and causing the thermal responsive means to be actuated to turn off or cut off the prime mover.

In some prior control devices the arrangement has been such that vapor or air was trapped in the vicinity of the thermal responsive means and so the thermal responsive means was not exposed directly to the flow of fluid through any conduit such as is the situation in the present invention. These air or vapor traps result in very undesirable and unreliable operation which the present invention overcomes.

Various changes may be made in the details of construction without departing from the spirit and scope of the invention as defined by the appended claims.

I claim:

1. A low liquid control device for a chamber containing liquid and vapor, comprising a conduit communicating with the chamber at approximately the low liquid mark therein, the conduit extending upwardly above the liquid level and outwardly from the chamber and being permanently open to the air at its upper end, and thermal responsive means adjacent the upper end of the conduit adapted to be actuated whenever the liquid in the chamber falls below the conduit and permits the vapor to pass through the conduit and contact the thermal responsive means.

2. In a system of the character described in which water at substantially boiling temperatures is circulated through the cooling jacket of a prime mover and through a steam-separating chamber having normally therein a liquid zone and a steam zone, the improvement which resides in providing a conduit having one of its ends in communication with the water zone and the other one of its ends in communication with thermostatically-operated means, said thermostatically-operated means being operated upon presence of steam in the conduit, said thermostatically-operated means comprising an electric switch connected to control the operation of said prime mover, said conduit extending outwardly from the chamber in substantially a horizontal direction and having the end thereof permanently sealed to provide an air-tight subchamber, said thermostatically-operated means being disposed adjacent the end of the conduit and being actuated whenever the

liquid in the chamber falls a sufficient amount to allow steam to enter the conduit and contact the thermostatically-operated means.

3. In a system of the character described in which water at substantially boiling temperatures is circulated through the cooling jacket of a prime mover and through a steam-separating chamber having normally therein a liquid zone and a steam zone, the improvement which resides in providing a conduit having one of its ends in communication with the water zone and the other one of its ends in communication with thermostatically-operated means, said thermostatically-operated means being operated upon presence of steam in the conduit, said thermostatically-operated means comprising an electric switch connected to control the operation of said prime mover, said conduit providing an air-tight horizontal subchamber which extends outwardly from the liquid zone and below the liquid level therein, said thermostatically-operated means disposed adjacent the outer end of the subchamber and being actuated whenever the liquid in the water zone falls a sufficient amount to allow the steam to enter the conduit and contact the thermal-responsive means.

4. A low liquid control device for a chamber containing liquid and vapor, comprising a conduit communicating with the chamber below the liquid level therein, the conduit extending upwardly to a level above the liquid level in the chamber, said conduit being permanently open to the air at its upper end, and thermal responsive control means adjacent the upper end of the conduit adapted to be actuated whenever the liquid in the chamber falls below the lower end of the conduit and permits the vapor to pass through the conduit and contact the thermal responsive control means.

5. A low liquid control device for a chamber containing liquid and vapor, comprising a conduit communicating with the chamber below the liquid level therein, the conduit extending upwardly to a level above the liquid level in the chamber and out from the chamber, said conduit providing an unobstructed passageway from the chamber below the liquid level therein to the air and being permanently open to the air, and control means adjacent the upper end of the conduit responsive to the heat of the vapor and adapted to be actuated by the vapor whenever the liquid in the chamber falls below the lower end of the conduit and permits the vapor to pass through the conduit and contact the control means.

6. A low liquid control device for a chamber containing liquid and steam, comprising means providing a passageway communicating with the liquid in the chamber below the surface thereof and leading upwardly above the liquid level and communicating with the air, said passageway being unobstructed throughout its length to provide permanent communication between the liquid body and the air, and control means adjacent the upper end of the passageway responsive to the heat of the vapor and adapted to be actuated by the vapor whenever the liquid in the chamber falls below the lower end of the passageway and permits the vapor to pass through the passageway and contact the control means.

7. In combination with a water cooled prime mover, a vapor phase unit for cooling the water used to cool the prime mover, the vapor phase unit including a chamber containing liquid and

vapor, means providing a passageway communicating with the liquid in the chamber below the surface thereof and leading upwardly above the liquid level and communicating with the air, and control means adjacent the upper end of the passageway responsive to the heat of the vapor to turn the prime mover off, said control means adapted to be actuated by the vapor whenever the liquid in the chamber falls below the lower end of the passageway and permits the vapor to pass through the passageway and contact the control means.

8. In combination as set out in claim 7 in which the passageway is unobstructed throughout to provide permanent communication between the liquid body and the air.

9. A device as set out in claim 6 in which the control means is positioned in the passageway so as to be directly subjected to the flow of vapor through the passageway.

10. A device as set out in claim 6 in which the control means is positioned in the passageway so as to be directly in the path of vapor flowing through the passageway.

11. A low water and excess pressure control device for a chamber containing liquid and vapor, comprising means providing a passageway communicating with the liquid in the chamber below the surface thereof and leading upwardly above the liquid level and communicating with the air, said passageway being unobstructed throughout its length to provide permanent communication of the liquid body and the air, and control means adjacent the upper end of the passageway responsive to the heat of the vapor or liquid and adapted to operate as a low liquid control whenever the liquid in the chamber falls below the lower end of the passageway and permits the vapor to pass through the passageway and contact the control means, said control means actuating as an excess pressure control device whenever the pressure in the chamber increases an extent such as to cause fluid to contact the control means.

5

12. In a system of the character described in which water at substantially boiling temperatures is circulated through the cooling jacket of a prime mover and through a steam separating chamber having normally therein a liquid zone and a steam zone, the improvement which resides in providing a conduit having one of its ends in communication with the water zone and the other one of its ends in communication with thermostatically operated means, said thermostatically operated means being operated upon presence of steam in the conduit, said thermostatically operated means comprising an electric switch connected to control the operation of said prime mover.

13. In a system of the character described in which water at substantially boiling temperatures is circulated through the cooling jacket of a prime mover and through a steam-separating chamber having normally therein a liquid zone and a steam zone, the improvement which resides in providing a conduit having one of its ends in communication with the water zone and the other one of its ends in communication with thermostatically-operated means, said thermostatically-operated means being operated upon presence of steam in the conduit, said thermostatically-operated means comprising means operative to control the operation of said prime mover.
